INSOLE FOR SKI-BOOTS

Einar Jacobsen, Halden, and Johannes Carlsson,
Oslo, Norway, assignors to A/S. Ostfold Sko-
fabrik, Halden, Norway

Application November 8, 1934, Serial No. 752,128
In Norway November 20, 1933

1 Claim. (Cl. 36—22)

In the manufacture of ski-boots of the special Norwegian quality, the insole is attached to the upper leather by means of a stitch made in a groove in the insole. This groove is made in such a manner, that along the insole edge somewhat distant therefrom an inclined cut is made which is directed towards the sole edge, whereupon the rib formed thereby may be turned up. The stitch is passed through the bottom of this groove and through the insole material so as to pass out through the sole edge and then through the upper leather. This method of manufacture presents no difficulty if the stitch is effected by hand, but if it is tried to effect the stitch in an ordinary shoe sewing machine, there arise difficulties, because the upwardly bent rib is too weak and flexible, and therefore it does not present a sufficient guide and rigidity to obtain a perfect stitch by means of the machine. For this reason, it has not been possible hitherto to obtain satisfactory results in the manufacture of ski-boots in shoe sewing machines. The present invention relates to an arrangement whereby this may be possible.

In the manufacture of welt-seam shoes the insole is connected with the upper leather by means of a double rib which is made partly by making a channel in the same manner as mentioned above in connection with stitching by hand in ski-boots and partly by making a channel horizontally in the exterior edge of the insole. By means of the last-named channel an outer rib is also formed which is bent up side by side with the ordinary inner rib and is pasted to same, whereby the combined rib provides great rigidity. However, this method has not been used in connection with ski-boots. According to the present invention such a combined or double rib is made in the same manner as used in the manufacture of welt-seam shoes, but the insole feather which in the last-named type of shoes is present outside the double-rib is, according to the present invention, cut away completely. In this manner a double, stiff and strong rib is obtained at the exterior edge of the insole, and this rib appears to be suitable for the manufacture of ski-boots in shoe sewing machines. The object of the present invention is consequently an insole per se made in the manner set forth above and suitable particularly for ski-boots. The invention also comprises ski-boots manufactured with such an insole.

The invention is illustrated in the annexed drawing. Fig. 1 shows the ordinary manner of connecting insole to upper leather. Figs. 2, 3 and 4 show the ordinary manner for the manufacture of insoles in welt-seam shoes, and Fig. 5 shows a portion of an insole made according to this invention. Figure 6 is a partial cross section of the finished shoe.

According to Fig. 1 the insole 1 is made in the ordinary manner with a rib 2 by making an inclined channel 3 in its bottom face somewhat distant from and along the exterior sole edge so as to leave between the bottom of the channel 3 and the sole edge material 4 forming an intermediate substance for the stitch 5 of pitched thread which has to connect the insole 1 with the upper 6, the exterior edge of which is bent outwards in ordinary manner as indicated at 7 to be sewn together with the outsole (not shown). This is the ordinary method used in the hand manufacture of ski-boots. As shown in Fig. 2 the insole 1 is provided, in a manner similar to that shown in Fig. 1, with an inclined channel 3 forming the inner rib 2 but is provided, in addition thereto, in the exterior edge of the insole 1 with a horizontal channel 8 directed straight inwards and forming an outer rib 9. When now the ribs 2 and 9 are bent up as indicated in Fig. 3 and are then pasted together as indicated in Fig. 4, a strong and stiff double rib is formed which provides the necessary support and guide for the sewing machine in sewing the insole together with the upper. The insole feather 10 left under the channel 8 is necessary in welt-seam shoes for the further manufacture of same.

Now according to the present invention the exterior feather 10 is cut away on the cutting line 30 a—a to obtain the insole shown in Fig. 5, wherein the double ribs 2, 9 are located at the exterior sole edge. The stiff rib thus obtained is found to be quite sufficient to enable a sewing-together of the insole 1 and the upper by means 35 of sewing machines. A connection is thereby obtained which is of a quality quite equivalent to a hand-stitched connection. An insole as shown in Fig. 5 thus constitutes an element in any sort 40 of ski-boots which is sewn with pitched thread in the sole portion.

As shown in Fig. 6, upon having made the 45 stitch 5 connecting insole 1 and upper 6, the outside 11 is sewn fast by a stitch 12, whereupon the last 15 is removed.

We claim:

An insole for ski-boots comprising a body portion and an edge portion, said edge portion being formed all around the sole edge except around the heel portion, with a double rib consisting of an exterior, upwardly bent rib and an interior upwardly bent rib, both ribs being integral with the sole body portion and pasted together along their adjacent faces, so as to constitute a combined rib along the outermost edge of the sole without any exterior projecting feather.

EINAR JACOBSEN. 60
JOHANNES CARLSSON.
